UNITED STATES PATENT OFFICE.

JOHN T. HAWKINS, OF TAUNTON, MASSACHUSETTS.

SHEET-DELIVERY MECHANISM FOR PRINTING-PRESSES.

SPECIFICATION forming part of Letters Patent No. 395,231, dated December 25, 1883.

Application filed June 6, 1885. Serial No. 167,830. (No model.)

To all whom it may concern:

Be it known that I, JOHN T. HAWKINS, of Taunton, in the county of Bristol and State of Massachusetts, have invented certain new and useful Improvements in Sheet-Delivery Mechanism for Printing-Presses, which invention or improvements are fully set forth and illustrated in the following specification and accompanying drawings.

- 10 The object of this invention is to provide a means of delivering the sheets from the top and front of a cylinder-press in which the impression - cylinder makes more than one revolution to an impression, so that said sheets 15 may be conveyed and laid upon a receiving-table with their last-printed sides upward without contact of the printed parts of said sides with any part of the mechanism during the process of delivery, and to do this with- 20 out obstructing access to either the inking-rollers or ink-fountain, suitable means being provided for cutting the sheets in one or more lines in the direction of their motion during the process of delivery.
- 25 The invention consists of the parts and combinations of parts, as hereinafter described, and set forth in the claims.

In the accompanying drawings, Figure 1 is a side elevation of so much of a two-revolution cylinder-press as is necessary to the full 30 illustration of the invention. Fig. 2 is an end elevation of the machine viewed from the left of Fig. 1.

In said figures the driving mechanism which 35 actuates the impression - cylinder, type-bed, inking apparatus, cylinder - grippers, and crank-shaft is omitted as not essential to the illustration of the invention. In said figures the respective parts are indicated by letters, 40 as follows:

A A' are the main frames.

A² A³ are vertical sliding pieces, in the upper ends of which the impression-cylinder B is journaled. The side pieces, A² A³, have a 45 small vertical motion (imparted to them by mechanism not shown) to raise the impression-cylinder clear of the type or form during the retrograde or non-printing stroke of the bed B' and to hold it in contact with the form

during the printing-stroke in a manner usual 50 with all two-revolution cylinder-presses.

B² is the form; B³, the ink-plate.

The circles R, Fig. 1, indicate the positions 55 of the form-rollers, and R' R' the positions of the angle distributing-rollers.

R² is the ink-fountain.

B⁴ are the bed-rollers, and B⁵ the bed-roller ways.

B⁶ is the feed-board.

Secured to the frames A A' are two standards, C C', carrying the fountain R², the bearings for the angle-rollers R', (not shown,) and the receiving-board C². Secured to the tops of the side pieces, A² A³, is a pair of standards, D D'. In the upper ends of the standards D D' is journaled a shaft, D². On the shaft D², outside of and close to standard D', is secured a gear-wheel, D³, and on a stud, D⁴, projecting from the standard D', runs an idler-wheel, D⁵, of the same diameter as and 65 meshing with the gear D³. On another stud, D⁶, projecting from the top side piece, A³, runs a second idler gear-wheel, D⁷, of the same 70 diameter as and meshing with the idler gear-wheel D⁵.

Secured to the shaft of the impression-cylinder B is a gear-wheel, D⁸, of half the diameter of the gear-wheels D³ D⁵ D⁷ and meshing with the gear-wheel D⁷. By means of the four gear-wheels last mentioned the shaft D² 80 is rotated once to every two revolutions of the impression-cylinder B. Secured to the shaft D² are two arms, E E'. In the free ends of the arms E E' is journaled a rock-shaft, F⁰, to which is secured a series of grippers, f. Attached also to the free ends of the arms E E' is a bar, E², upon which the points of the grippers f close. The bar E² has notches f' 85 cut in its outer edge at points not covered by the grippers f for the passage of the oscillating grippers, hereinafter described, and of the cylinder-grippers g. The grippers f are operated to close upon the bar E² by a spring, f². To the end of rock-shaft F⁰, outside of and close to the arm E', is secured a lever, f³.

Pivoted to a stud, f⁴, projecting from the arm E', is a lever, f⁵, carrying a roller, f⁶. Levers f³ f⁵ are connected by a rod, f⁷, pivoted to 95

each. Secured to standard D' is a stationary cam, f⁸, engaging the roller f⁶, and so formed and placed as to open and allow the spring f² to close the grippers f at two places, as 5 hereinafter described. The cylinder-grippers g are operated in any usual way to receive the sheet from the feed-board B⁶ and to release it to the grippers f as they close upon it.

10 G is a grooved sector secured to shaft D², a portion of which is projected at G', Fig. 1, to show the groove.

G² is a rotary knife carried in bearings G³, which are in turn secured to a rod, G⁴, which 15 extends between the two brackets A² A³. The knife G² engages the groove in the sector G for the purpose of dividing the sheets as delivered in the direction of their motion, as is often required.

20 W W are weights for counterbalancing the parts attached to the shaft D².

The shaft F is journaled in the frames A A', and by suitable gearing (not shown) is made to revolve once for every two revolutions of the impression-cylinder B, or once to

25 each sheet printed. Secured to shaft F is a crank-disk, F'. Journaled in the standards C C' is a rock-shaft, F². Secured to shaft F², adjoining the standard C, is a bell-crank lever, F³, and on the side adjoining the standard C' a single-armed lever, F⁴. The short arm of the bell-crank lever F³ is connected to the crank-pin F⁵ by a connecting-rod, F⁶. In the free ends of levers F³ F⁴ is journaled a 30 rock-shaft, a, to which is secured a series of grippers, a'. Secured in the free ends of the levers F³ F⁴ is also a stationary rod, a², to which is secured a series of tongues, a³, against which the grippers a' close by the action of a spring, a⁴. To the rock-shaft a is secured a two-armed lever, a⁵, having a notch, a⁶, cut in its lower arm.

35 Mounted loosely upon the rod a² is a two-armed lever, a⁷, whose short arm is made to engage the notch a⁶ and a corresponding arm of the lever a⁵ by the spring a⁸. A stop-pin, b, erected from and secured to the receiving-board C², engages the upper arm of lever a⁵ at the outward extremity of the motion of 40 the arms F³ F⁴, thus opening the grippers a'. The lever a⁷, by the action of spring a⁸, is 45 then caused to engage the notch in the lever a⁵ and hold the grippers open until, upon the inward extremity of the motion of the levers 50 F³ F⁴, the roller b', carried on the end of the shaft F⁰, engages the long arm of the lever a⁷, thus throwing said lever's short arm out of the notch in the lower arm of the lever a⁵ and allowing the grippers a' to again close by the 55 action of the spring a⁴.

60 The operation of the above-described devices is as follows: A sheet being taken from the feed-board B⁶ by the cylinder-grippers g is held thereby until printed during the first 65 revolution of the impression-cylinder B. The gears D⁸ D⁷ D⁵ D³ cause the arms E E', and

with them the grippers f, to arrive at the proper time to take the advancing edge of the sheet at the same moment of time as released by the cylinder-grippers g, the grippers f being opened and closed by one of the elevations on the cam f⁸ acting upon the roller f⁶. The sheet is then carried into position, as shown by the dotted lines S, Fig. 1, the arms E E' and the levers F³ F⁴ being 70 shown in position in dotted lines at S' S², Fig. 1, when the grippers a' close upon the sheet, arresting its further progress simultaneously with the grippers f, being again opened by the other elevation of the cam f⁸. The arms 75 F³ F⁴ are then carried, by the operation of the crank-pin F⁵, into position shown at S³, Fig. 1, the stop-pin b releasing the sheet to fall upon the receiving-board C², as indicated by the dotted lines S⁴ and as limited by a sheet-stop, S⁵. During the printing of the succeeding sheet the arms F³ F⁴, and with them the grippers a', are carried back to meet the arms E E' upon their next revolution to take the 80 succeeding sheet.

85 I do not confine myself to the method herein described of operating the rotary arms E E' and their grippers f, nor to making the same to describe one revolution to each two revolutions of the impression-cylinder, as it is obvious that they may make the same number of revolutions as the impression-cylinder and be geared directly to it by one pair of wheels only, and that the rock-shaft F² and oscillating arms F³ F⁴ may be brought into proper 90 position to meet such construction; nor do I confine myself to the method shown for operating the levers F³ F⁴ and their grippers a', as said parts may be actuated to fulfill their functions in many ways, as best suited to the 95 remaining mechanism of the machine. I do not herein claim the mechanism shown for cutting the sheets, nor confine myself to the use of any form of sheet-cutting mechanism.

100 Having thus fully described my said improvements, as of my invention I claim—

1. In a cylinder printing-press, in combination with its impression-cylinder and a continuously-rotating gripper mechanism, an oscillating mechanism provided with a series of 105 grippers, as a', adapted to receive the sheets from said rotating gripper mechanism, whereby the sheets are first taken from the top and front of the impression-cylinder by rotating grippers and then received therefrom by oscillating grippers and further delivered therefrom to any suitable receptacle, substantially as and for the purposes set forth.

110 2. In a cylinder printing-press, in combination with an impression-cylinder, as B, provided with grippers, as g, a sheet-delivery mechanism consisting of carriers, as E E', operated continuously in a circle and provided with grippers, as f, taking the sheets from the top and front of said impression-cylinder, 115 carriers, as F³ F⁴, oscillating back and forth and provided with grippers, as a', a receiv-

ing-board, as C², and means, substantially as described, for opening and closing said three sets of grippers at the proper times, whereby the sheets are taken from said impression-
5 cylinder and conveyed to and dropped upon said receiving-board with their last printed sides upward, without contact of the printed

parts of said sides with any part of the mechanism, substantially as set forth.

JOHN T. HAWKINS.
